UNITED STATES PATENT OFFICE.

ARTHUR G. CARLSON, OF NORTH EASTON, MASSACHUSETTS.

DETECTOMETER.

1,155,338.

Specification of Letters Patent.

Patented Oct. 5, 1915.

Application filed June 11, 1913. Serial No. 772,955.

To all whom it may concern:

Be it known that I, ARTHUR G. CARLSON, of North Easton, in the county of Bristol and State of Massachusetts, have invented 5 the new and useful Detectometer, of which the following is a specification.

In certain of the electrical arts and more especially in what are known as wireless systems, it becomes highly desirable at times to 10 rapidly establish or reestablish definite conditions of pressure and engagement or relationship between two elements such, for example, as contacts; and it is one of the principal objects of the present invention to 15 provide means whereby an exceedingly delicate adjustment of elements of this description may be made in substantially a minimum time and with little effort or attention.

In wireless telegraphy, for example, it is 20 known to use two contact elements one of which, is, in certain systems, a mineral cup and the other a pin the point of which bears upon the surface of the mineral in the cup. In such systems it has been found in practice 25 that for an engagement of the pin point with a particular mineral and at a determined point upon said mineral, one pressure and but substantially only one pressure exerted by the pin point or its equivalent, 30 against the mineral is best adapted for the reception of messages from a determined distance under determined light and other wave affecting conditions, and from a transmitter affording impulses of a determined 35 wave length and strength. Frequently heretofore, an operative has been obliged to ascertain this particular contact condition by repeated trials, which sometimes consumes as much as fifteen minutes' time; and when 40 from a slight jar or for any other cause, the requisite contact condition is dis-established, he is then obliged to repeat his trials to re-establish the same. In the case of a shipwreck, for example, such loss of time might 45 prove fatal.

My invention when applied to wireless telegraph apparatus substantially obviates this serious difficulty and when once the desired contact condition has been ascertained, 50 even though it may be repeatedly lost by jars or from other cause, it may be as repeatedly reestablished, immediately and with ease.

In the accompanying drawing I have exemplified a preferred construction embodying my invention, but as I am aware that

various changes and modifications may be made herein, and various uses may be made hereof, I desire to be limited only by the scope of said claims, broadly considered in 60 the light of my disclosure.

Referring to the drawing, in which like characters of reference designate like parts in the respective views, Figure 1 is an elevation partly in section of a device embodying 65 my invention and particularly adapted for wireless telephone and telegraph apparatus; Fig. 2 is a plan of the same; Fig. 3 is a partial section at line 3—3 of Fig. 2; and Fig. 4 illustrates a modification.

Frame or support A carries binding posts a a', post a having electrical connection with bracket B and post a' having electrical connection with mineral cup D. Mounted on bracket B is thumb screw B' integral with 70 which is pin b'. Post E supports bracket e which is a bearing for a pin d which is suitably connected to the mineral cup D; the mineral being preferably silicon although it might be carborundum, copper pyrite or 75 other suitable material. Pin d engages a flat spring F which is curved as shown and suitably connected to the frame at f. At f' a steed rod f² is soldered, or otherwise suitably connected, to the spring F; the rod 80 being bent to engage a slotted arm f³ projecting from the balance wheel G which is rotatably mounted on bearing G'. Rigidly connected to wheel G is a pointer G² in 85 adjacency to a gage G³ having suitable indicating marks thereon.

The operator turns the thumb screw until he is satisfied by repeated trial that the aforesaid desired contact conditions between the pin b' and cup D, which give the most 90 efficient results, have been attained. The movement of the thumb screw moves the cup and, through the intermediary of rod d, the spring, which in turn rotates the wheel 95 and moves the pointer along the gage. He 100 may find that when the pointer is at mark 3 on the gage the action is most efficient for conditions at that time. It will very likely happen that mechanical shaking or the jar- 105 ring due to the sending of messages from, for example, a companion instrument or the heavy discharge of static, or from various other causes, will change the condition of engagement between pin b' and cup D; but in my apparatus, in such case, all that the 110 operator needs do is to turn the thumb screw to restore the pointer to its position oppo-

site mark 3. It will be observed that a slight movement of pin d will give a large movement to the bent end of rod f^2 , and this movement will be again multiplied on account of the length of the pointer so that a very slight change in the condition of engagement of pin b' and cup D will not only be registered but will be registered with the greatest accuracy with reference to the gage.

10 In Fig. 4 the cup H is stationary and the spring H' carries a nut H² to vary the engagement between pin H³ and cup H; the condition of engagement being indicated by pointer H⁴ in adjacency to gage H⁶, in this instance, directly, the thumb screw H⁵ carrying pin H³ and moving the nut H².

It will be clear that my invention is useful not only for wireless telegraphy and wireless telephony but also for a number of other purposes; but it is of special value in wireless apparatus.

What I claim is:

1. A detectometer comprising an adjusting member; a mineral cup movably mounted and adapted to be electrically engaged by, and moved by, the adjusting member; a spring moved by said cup; a wheel rotated by said spring; a pointer swung by said wheel; and a gage in adjacency to said pointer.

2. A detectometer comprising an adjusting member; a mineral cup member movably mounted and adapted to be electrically engaged by, and moved by, the adjusting member; a spring member having one end fixed and one end free and being engaged relatively near its fixed end by said cup member; a balance wheel rotated by the free end of said spring; a gage; a pointer rigidly connected to said wheel and having its free end moving in adjacency to said gage, the distance from the free end of the pointer to the axis of said wheel being very great relatively to the distance from the axis of the wheel to the point of engagement of the wheel and spring.

3. A wireless system detectometer comprising a plurality of elements which when disposed in an exactly determined contact

relationship with respect to each other, normally establish operative conditions in said system most favorable to the operation thereof, one of said elements comprising a rectifying mineral and another of said elements being a member adapted to exert a compressive effort upon said mineral, movable means for establishing said relationship, and means subject to the action of said movable means, for indicating how much movement of the latter is required to restore said relationship when the same has been disestablished, said indicating means including mechanism for amplifying a displacement of one of said elements resulting from the compressive effort exerted upon said rectifying mineral, said displaced element having a connection with said amplifying mechanism, which connection is normally under a compressive stress corresponding to said compressive effort.

4. A wireless system detectometer comprising a plurality of elements which when disposed in an exactly determined contact relationship with respect to each other, normally establish operative conditions in said system most favorable to the operation thereof, one of said elements comprising a rectifying mineral and another of said elements being a member adapted to exert a compressive effort upon said mineral, movable means for establishing said relationship, and means, subject to the action of said movable means, for indicating how much movement of the latter is required to restore said relationship when the same has been disestablished, said indicating means including mechanism for amplifying a displacement of one of said elements resulting from the compressive effort exerted upon said rectifying mineral, said displaced element having a connection with said amplifying mechanism, which connection is normally under a stress corresponding to said compressive effort.

ARTHUR G. CARLSON.
